US00D876971S

(12) **United States Design Patent** (10) **Patent No.:** **US D876,971 S**
(45) **Date of Patent:** **** Mar. 3, 2020**

(54) **THERMOSTAT**

(71) Applicant: **Johnson Controls Technology Company**, Auburn Hills, MI (US)

(72) Inventors: **Joseph R. Ribbich**, Waukesha, WI (US); **Julio A. Abdala**, SW Ranches, FL (US); **Juan Guillermo Alvarez**, Weston, FL (US); **Felipe M. Bicudo**, Fort Lauderdale, FL (US); **Vinosh C. Diptee**, Boynton Beach, FL (US); **Patricia Ellis Douglass**, Pompano Beach, FL (US); **Hao A. Nguyen**, Lake Worth, FL (US); **Claudio Santiago Ribeiro**, Evanston, IL (US); **Amit Verma**, Sunrise, FL (US)

(73) Assignee: **Johnson Controls Technology Company**, Auburn Hills, MI (US)

(**) Term: **15 Years**

(21) Appl. No.: **29/680,613**

(22) Filed: **Feb. 18, 2019**

Related U.S. Application Data

(60) Continuation of application No. 29/618,404, filed on Sep. 21, 2017, now Pat. No. Des. 843,247, which is (Continued)

CLAIM

We claim the ornamental design for a thermostat, as shown and described.

DESCRIPTION

FIG. 1 is a front perspective view from above of the claimed design for a thermostat;

FIG. 2 is a front side view of the claimed design of FIG. 1; FIG. 3 is a rear side view of the claimed design of FIG. 1; FIG. 4 is a right side view of the claimed design of FIG. 1; FIG. 5 is a left side view of the claimed design of FIG. 1; FIG. 6 is a top view of the claimed design of FIG. 1; and, FIG. 7 is a bottom view of the claimed design of FIG. 1. The broken lines in the drawings form no part of the claimed design. Oblique lines represent transparent or semi-transparent portions of the claimed design.

1 Claim, 7 Drawing Sheets

Related U.S. Application Data

a division of application No. 29/563,447, filed on May 4, 2016, now Pat. No. Des. 810,591, which is a continuation-in-part of application No. 29/548,334, filed on Dec. 11, 2015, now Pat. No. Des. 790,369.
